UNITED STATES PATENT OFFICE.

THOMAS F. PAYNE, OF PITTSBURG, PENNSYLVANIA.

SHOWER-BATH CONSTRUCTION.

999,858.

Specification of Letters Patent. Patented Aug. 8, 1911.

Application filed July 21, 1910. Serial No. 573,091.

To all whom it may concern:

Be it known that I, THOMAS F. PAYNE, residing at Pittsburgh, in the county of Allegheny and State of Pennsylvania, a citizen 5 of the United States, have invented or discovered certain new and useful Improvements in Shower-Bath Construction, of which improvements the following is a specification.

10 My invention relates to improvements in the construction of shower baths, and it has for its object a simple, secure, and sanitary arrangement of parts.

In the accompanying drawings which 15 form part of this specification, Figure 1 is a plan view of three adjoining shower baths which in their construction embody my present invention; Fig. 2 is an incomplete vertical section on the line II—II of Fig. 1; 20 Fig. 3 is a vertical section on a plane at right angles to that of Fig. 2 and on a somewhat larger scale than Figs. 1 and 2, the plane being indicated by the line III—III Fig. 1; Figs. 4 and 5 show in side and end elevation, and on much larger scale, a detail 25 of construction; Figs. 6 and 7 in like manner illustrate another detail, Fig. 7 being in this case a view in vertical section; Figs. 8 and 9 illustrate in like manner a third detail of construction, these figures showing 30 the parts in elevation, and from points of view at right angles to one another.

Parts which are repeated in the several 35 figures bear the same reference numerals in each case.

The shower-bath structure consists essentially of a basin portion 1 and a screen portion 2. The material of which these parts are composed is not in any degree essential 40 to my invention, but ordinarily the basin portion will be formed of enameled iron, and the screen portion of slabs of marble or slate.

45 The basin portion for each individual shower is made preferably of a single integral piece, with a discharge orifice 3 at the lowest point of its central dished portion, and a peripheral supporting flange 4. Continuous with this peripheral supporting 50 flange 4 are means for assembling the screen portion with the basin portion, which will presently be described in detail. The basin portion is preferably so designed, as by the reinforcing flanges 11 that it may rest upon 55 a joist or other framework of a building, and so the rim of the basin portion may be

brought flush with the floor of the room in which the shower bath is installed. This is advantageous; in ordinary construction of shower-bath booths, particularly for domestic installation, there is a sill or splash board across the entrance to the shower-bath booth.

The screen portion of the shower bath in my improved construction rests upon the 60 flange 4 of the basin portion; and, since the basin may rest upon the frame of the building, as I have explained, the framework of the building may be made to support the entire structure.

70 The further features of my invention consist in the means for securing the screen portions in place upon the flange portions 4. Where the flange portion 4 lies in the outer perimeter of the entire structure, it is preferably provided with an upturned retaining edge 5, serving to retain the screen portion 2 from outward displacement and to prevent the escape of water outward from beneath the lower edge of the screen. The upper 75 surface of the flange 4 is further preferably provided with buttons 12 upon which the lower edges of the marble screen will rest while leaving a space for the drainage of water inward. Where the flange extends 80 along the flange of an adjacent basin portion (that is where the flanges of two basins meet), such further details are employed as are indicated in Figs. 4 to 9, inclusive. 85 These figures show three successive portions 90 of the seat for the screen, the three portions being the front, the back, and an intermediate point along the rim of the basin. In these Figs. 4 to 9 is illustrated the meeting of the rims of two adjacent basin portions. 95 At either end, the flange portions are provided with down-turned lugs 6, which may be bolted together to secure the adjacent basins together. In addition to these lugs for bolting, a seat 7 is provided, which 100 serves both to receive the lower edge of the screen 2 and to secure more firmly and by sanitary joint the bodies of the basins. To this end, the seat 7 is provided, preferably at intervals, with oppositely placed upwardly extending lugs 8 successively illustrated in Figs. 4, 6, and 8, through which the lower edge of the screen portion may be bolted to place; and is also provided with oppositely disposed surfaces 9, which take 105 over the rims of the adjacent basins, and which render more secure in their engage-

- ment by the weight of the screen 2 from above, more securely hold the basins in relative positions. A spacing web 10 preferably extends from this seat member 7, between the flanges 4 of the adjacent basin portions. It will be observed that the opposite surfaces 9 of the screen seat are not only so arranged as to secure the adjacent basin portions in their predetermined relative positions, but these surfaces 9 are downwardly inclined and accordingly they are so disposed as to shed water and so to remain clean and sanitary.
- It will be understood that in the construction of a single shower-bath booth, to be installed alone, the particular construction employed at the meeting of two adjacent booths will be dispensed with, and the rim flange will be continued around all three sides.
- I claim herein as my invention:
1. In a shower-bath structure, the combination of a basin and a screen, said basin being provided with a peripheral flange, said basin arranged to rest upon the framework of a building to afford support from beneath, and said flange arranged to sustain the screen portion resting upon it above and to form a drain passage beneath the edge of said screen portion, substantially as described.
  2. In a shower-bath structure, the combination of a flanged basin portion and a screen portion resting on the flange of said
- basin portion, the bearing surface of said flange being shaped to form a drain passage beneath the edge of said screen portion, substantially as described.
3. In a shower-bath structure, the combination of two adjacent basin portions, each provided with a peripheral flange, a screen seat resting upon said flanges, and having oppositely arranged surfaces engaging the rims of said basin portions, substantially as described.
4. In a shower-bath structure, the combination of two adjacent basin portions provided with peripheral flanges extending in proximity to one another, a screen seat resting upon the said flanges, and provided with a spacing web extending between the proximate edges of said flanges, substantially as described.
5. In a shower-bath structure, a combination of two adjacent basin portions, each provided with a peripheral flange and with oppositely arranged downwardly inclined surfaces, a screen seat resting upon said flanges and having surfaces engaging the aforesaid opposite and downwardly inclined surfaces of the adjacently-placed basin portions, substantially as described.

In testimony whereof, I have hereunto set my hand.

THOMAS F. PAYNE.
